United States Patent Office

Des. 210,791

Patented Apr. 16, 1968

210,791

AERIAL TOY

Roy D. Tally, 933 University Ave., and Lars Edgar
Oystol, 811 17th St., both of Boulder, Colo. 80302

Filed Apr. 1, 1966, Ser. No. 1,731

Term of patent 14 years

(Cl. D34—15)

FIG. 1

FIG. 4

FIG. 5

FIG. 2

FIG. 3

FIG. 1 is a top plan view of an aerial toy showing our new design;

FIG. 2 is a side elevational view thereof;

FIG. 3 is a perspective view thereof;

FIG. 4 is a section taken along the line 4—4 in FIG. 1; and

FIG. 5 is a section taken along the line 5—5 of FIG. 1.

We claim:

The ornamental design for an aerial toy, substantially as shown.
